UNITED STATES PATENT OFFICE.

WOODFORD O. SEAT, OF NASHVILLE, TENNESSEE, ASSIGNOR OF ONE-HALF TO ROBERT H. WALLER, OF NASHVILLE, TENNESSEE.

CONCRETE WALL CONSTRUCTION.

1,046,029.

Specification of Letters Patent.

Patented Dec. 3, 1912.

Application filed December 5, 1910. Serial No. 595,697.

To all whom it may concern:

Be it known that I, WOODFORD O. SEAT, citizen of the United States, residing at Nashville, in the county of Davidson and State of Tennessee, have invented a new and useful Concrete Wall Construction, of which the following is a specification.

This invention relates to improvements in concrete walls, and the object of the invention 10 is to provide a wall which will be proof against dampness, which will be thoroughly bonded and which may be built rapidly and economically.

The invention also has for its object a 15 construction whereby the wall may be readily built without the use of forms, and which may be easily erected in a true vertical plane.

The stated objects, and other incidental 20 objects which will appear hereinafter, are attained in the use of the device illustrated in the accompanying drawings, and the invention consists in certain novel features of the same which will be hereinafter first fully 25 described and then more particularly pointed out in the appended claims.

In the drawing, I have shown a sectional perspective view of a portion of a wall embodying my invention.

30 In carrying out my invention, I provide a foundation 1 which may be of any desired size according to the building to be erected and may, of course, be of any material, but I prefer to employ concrete. When the 35 foundation has reached the proper height a coping or facing 2 may be set in or formed upon the front side of the same so as to give a neat finish to the foundation at the point where the wall proper begins. Upon 40 the upper surface of the foundation and the said facing, I then spread two lines of mortar or cement, indicated at 3, which respectively follow the front and rear sides of the foundation, as clearly shown. At intervals 45 along both these lines of cement or mortar, I place braces or bonding bars 4 which extend diagonally upward and are provided at their lower ends with feet 5 resting upon the foundation and having spurs 6 projecting upward from their extremities. The 50 main portions of these braces or bonding bars extend upward obliquely and the upper ends of the bars are provided with horizontally disposed heads or shoulders 7 having lips 8 at their extremities. These lips 55

8 may be turned downward or upward and in actual practice it will be found desirable to have the lips of the alternate braces extend in opposite directions. The brace bars having their lips turned downward will 60 preferably be provided at the ends of their heads or horizontal portions 7 with lugs 9 extending slightly upward to aid in centering the blocks which will be utilized in building the wall. At intervals along the 65 lines of cement or mortar I provide the horizontal tie bars 10 which will rest directly on the foundation and will have lips 11 at their ends corresponding to the spurs 6 at the lower ends of the brace bars 4. The 70 several brace bars and tie bars being thus placed in position, concrete blocks 12 having longitudinal grooves 13 in their edges are placed upon the lines of cement or mortar with the grooves fitting over the upturned 75 spurs 6 and lips 11, as will be readily understood. The weight of the blocks will cause them to sink in the cement or mortar so that the space between the bottom of the blocks and the space within the grooves in 80 the blocks will be entirely filled with the mortar and a close tight joint thereby effected. The upturned spurs 6 and teeth 11 will aid in bringing the blocks into the proper position over the front and rear 85 sides of the foundation, and the blocks may be leveled and brought into the exact position they should occupy in the finished wall by the usual methods of masonry. The lips 8 at the upper ends of the brace bars are 90 brought into engagement with the grooves 13 in the upper edges of the blocks and the blocks will thus be thoroughly braced and held in their proper relative positions. The first course of blocks having been thus laid, 95 a second row of straight tie bars 10 is laid upon the said blocks and a second row of crossed, diagonally extending brace bars 4 is also placed in position upon the blocks. The mortar is then applied and a second 100 row of blocks laid upon the first row with the joints in the superposed row breaking joint with the under row. The wall may thus be carried to any desired height in an expeditious manner without the use of 105 any forms and without any loss of time occasioned ordinarily by waiting for the green concrete to set. The horizontal tie bars 10 may be provided with lugs 14 corresponding to the lugs 9 on the brace bars 4, and 110

the said horizontal tie bars will be so disposed that the alternate bars in any one row will have the lips at their ends extending in opposite directions so that the transverse bonding or tying force will be applied to the upper edges of one row of blocks and in the same plane to the lower edges of the superimposed row of blocks. In this manner the wall will be very thoroughly braced throughout its extent.

It will be observed on reference to the drawings that the spurs or lips at the ends of the several braces and tie bars will engage the inner wall of the groove in the blocks so that the blocks will be properly spaced and will be effectively bonded. These lips or spurs, and the lugs adjacent the same, also serve as guides to aid in bringing each superposed block into its proper position upon the subjacent block so that the work involved in making the wall plumb is reduced to a minimum. The wall may be pointed up and finished in the usual manner, and the outer surface may be given any desired ornamental appearance. At the proper points of the wall I will place over the blocks of the inner member of the wall a timber seat 15 in which the end of a joist 16 may be supported.

30 A wall constructed as illustrated and as herein described will present substantially two independent inner and outer walls separated by a continuous air space coextensive with the walls so that the access of moisture and dampness to the inner wall and through the same to the interior of the building will be positively prevented. The walls may be built of thoroughly dried compressed concrete blocks so that settling or cracking of the walls will be reduced to a minimum, and the walls are braced in such a manner that the vertical position of the same will be effectually maintained. It will be readily noted that the corresponding edges of the 45 parallel blocks are connected by the horizontal tie-bars and that the lower edges of the blocks in each row are connected with the upper edges of the blocks in the parallel row by the diagonal braces so that the two 50 wall members will be connected and braced against strain in every direction. If, for any reason, it is desired to have a very heavy wall the space between the inner and outer members may be filled with liquid cement or similar material so that a thick, 55 solid wall will be rapidly formed without the use of any of the well known false work.

The advantages of the construction and of the method of operation will be readily apparent to those skilled in the art to which the invention appertains, and while I have described the principle of operation of the invention, together with the apparatus which I now consider to be the best embodiment thereof, I desire to have it understood

that the apparatus shown is merely illustrative, and that such changes may be made when desired as are within the scope of the claims appended hereto.

Having thus described my invention, what I claim is:

1. A concrete wall comprising inner and outer rows of superposed concrete blocks having longitudinal grooves in the edges constituting the upper and lower edges of the laid rows, a filling of cementing material between the superposed blocks entering the grooves in the blocks, and tie bars having their opposite ends extending between superposed blocks of the respective rows and provided at their extremities with lips projecting in opposite directions with respect to the intermediate portions of the bars, the lip ends of the bars being embedded in the cementing material, and the tie bars extending diagonally upward from one end toward the other end and alternating in direction from one row of superposed blocks to the like blocks of the other row, the lip on one end of a bar extending upwardly into the groove of the block and the lip at the other end of the bar extending downwardly into the groove at the opposite edge of the corresponding block of the other row.

2. A wall composed of spaced rows of superposed concrete blocks, each block having longitudinal grooves on the edges constituting the upper and lower edges when laid in a wall, and tie bars extending across the space between the rows of blocks and having their ends entering the respective rows of blocks at the joints and terminating in lips engaging in the grooves in the blocks, the tie bars each extending from the joint between two blocks of one row to the joint between two blocks of the other row at a higher point on the other row than the first named blocks.

3. A concrete wall comprising inner and outer rows of superposed concrete blocks having longitudinal grooves in the edges constituting the upper and lower edges of the laid blocks, a filling of cementing material between the superposed blocks, said material entering the grooves in the blocks, and tie bars having their opposite ends extending between superposed blocks of the respective rows and provided at their extremities with lips entering the grooves in the respective blocks, the lipped ends of the bars being embedded in the cementing material, the tie bars extending diagonally upward from one end toward the other and alternating in direction from one row of superposed blocks to the other.

4. A concrete wall comprising inner and outer rows of superposed concrete blocks having longitudinal grooves in the edges constituting the upper and lower edges of the laid rows, a filling of cementing mate-

rial between the superposed blocks, said material entering the grooves in the blocks, and tie bars having their opposite ends extending between superposed blocks of the respective rows and provided at their extremities with lips entering the grooves in the respective blocks, the lipped ends of the bars being embedded in the cementing material, the tie bars extending diagonally upward from one end toward the other and alternating in direction from one row of super-

posed blocks to the other, there being also other lipped tie bars extending between and anchoring in corresponding blocks at the same level in the rows of superposed blocks. 15

In testimony, that I claim the foregoing as my own, I have hereto affixed my signature in the presence of two witnesses.
